UNITED STATES PATENT OFFICE.

ALEXANDER STRUTHERS, OF LONDON, ENGLAND.

WINDOW OPENING AND CLOSING DEVICE.

1,142,207.

Specification of Letters Patent.

Patented June 8, 1915.

Application filed June 3, 1912. Serial No. 701,206.

To all whom it may concern:

Be it known that I, ALEXANDER STRUTHERS, a subject of His Majesty the King of Great Britain, residing at London, in the 5 county of London, England, have invented certain new and useful Improvements in Window Opening and Closing Devices, of which the following is a specification.

This invention relates to improvements in 10 and connected with windows and has reference to windows of the type wherein the sashes are pivoted.

The present invention has for its object to improve and simplify the construction of 15 such windows and consists in various improvements in construction and detail designed to render such windows convenient and effective in operation and of comparatively inexpensive construction.

20 The accompanying drawings illustrate my invention Figure 1 being a front elevational view of the window with one of the sashes partly opened for ventilating purposes. Fig. 2 a side sectional view on line A. B. C.

25 D. E. F. of Fig. 1. Figs. 3 and 4 face views illustrating the special form of pivot employed. Fig. 5 is an elevational view and Fig. 6 a section on line G. H. of Fig. 5 showing a means for maintaining the window 30 sash at certain predetermined angles.

Referring to these drawings wherein like letters of reference indicate corresponding parts wherever occurring, the numeral 1 designates the window frame and 2 the supplemental stiles to which the sashes 3 are pivoted. The supplemental stiles pivotally connected to one sash are connected to the supplemental stiles pivotally connected to the coöperating sash by means of cords or 40 the like 4 passing over pulleys 5 so that the one window balances the other. The pivotal connections which forms no part of my invention but, by means of which the sashes 3 are connected to the supplemental stiles 2 45 are shown in Figs. 3 and 4 and consist of two members 6 and 7 one of which carries attached to or integral with it the pivot proper 8 and has a recessed or cut away part 9. The other member 7 is provided with an 50 opening or bearing 10 to accommodate the pivot 8 and has an exactly similar cut away or recessed portion 11 so that when the two members 6 and 7 are fitted together the one is capable of turning relative to the other through an angle of 90°. This form

of pivotal connection has the advantage that when the sashes are in the normal closed or vertical position there is no gap presented to the view.

In order to enable the sashes to be held at 60 an angle to the vertical for ventilating purposes I provide the fitting 12 which is provided with slots 13 slidably respectively upon the pin 14 and the thumb screw 15 carried upon a fixed plate 16 attached to the window 65 frame. Thus the fitting 12 is capable of adjustment within the limits of the slots 13 and the thumb nut or thumb screw 15 serves to secure the fitting 12 in the desired position. A suitable knob 17 may be provided as shown to facilitate the adjustment. The fitting 12 carries in any suitable manner 70 the arms 18 which are pivotally or loosely connected and are provided at their free ends with hooks 19 which in operation engage pins or hooks 20 provided upon the sashes. In order to provide for the limited adjustment of the effective lengths of the cords 4 the fittings 21 to which they are connected are provided with screw threaded 75 ends so that such fittings can be screwed more or less into the supplemental stiles 2 and if it is desirable to provide for the possibility of having both sashes located at the top of the window the cords may be entirely 80 disconnected from supplemental stiles and anchored to a suitably located hook on the window frame. Further in order to facilitate repairs and redecoration of the sashes the cords can be entirely disconnected from 85 the sashes and the sashes removed. The sashes 3 may also be held at certain predetermined angles to the frame by the method in Figs. 5 and 6. A well fitting 21 is housed in the member 6 and secured thereto by 90 screws 22 passing through the lugs 23 on the fitting. This well contains a piston 24, with a hemi-spherical or other suitably shaped head 25 and a spring 26. In the member 7 are three (there may be more or less) bores 27 equidistant from the axis of rotation and at the same distance therefrom as the piston 24. When the sash 3 is swung from the vertical position between the supplemental stiles 2, the hemispherical or other suitably shaped head 25 of the piston 24 is forced successively into the bores 27 in any one of which it will rest if the turning effort is discontinued. The bores 27 may be in the member 95 100 105 110 6 and the piston 24 in the member 7.

What I claim and desire to secure by Letters Patent is:—

The combination with a window frame and sashes pivotally held in the frame, of a plate fixed to the frame, pins carried by the stationary plate, a movable plate having slots the slots adapted to accommodate the pins, for holding the movable plate into engagement with the fixed plate, a pin carried by each sash, arms having hooked ends, carried by the movable plate, the hooked

ends of the arms adapted to engage the pins for holding the sashes in an adjusted position with relation to their frames and means for holding the movable plates in its positions of adjustment. 15

In testimony whereof, I affix my signature in the presence of two witnesses.

ALEXANDER STRUTHERS.
